A CORPORATION OF NEW JERSEY.

MERCURY-VAPOR-ARC LAMP.

1,204,117,

Specification of Letters Patent.

Patented Nov. 7, 1916.

Original application filed August 25, 1904, Serial No. 222,148. Divided and this application filed November 12, 1915. Serial No. 61,160.

To all whom it may concern:

Be it known that we, CHARLES ORME BASTIAN and ALBERT EDWARD SALISBURY, subjects of the King of Great Britain, and residents of London, England, have invented certain new and useful Improvements in Mercury-Vapor-Arc Lamps, of which the following is a specification.

This invention relates to electric lamps of the character known as "vapor lamps" or "mercury vapor lamps" or "vapor arc lamps"; and comprises an exhausted or any other suitable chamber for containing mercury or other suitable volatilizable material of suitable electrical conductivity (all of which for the sake of brevity we will hereinafter refer to as "mercury") this chamber or container being provided with electrodes or contacts at the desired distance apart. The mercury in the container is in such position therein and in sufficient quantity to normally electrically connect the two aforesaid electrodes or contacts for starting the lamp, the arrangement and operation being such that when the current is first sent through the lamp and through the mercury connecting the aforesaid electrodes or contacts thereby the mercury is automatically caused to recede or divide into separate bodies or caused to recede from one of the contacts and thereby the mercury is vaporized and the arc is struck or luminosity produced and the length of the arc or luminous space is extended or prolonged up to any practical length within the limits of the lamp.

We will now describe our present invention (as carried into practice) with reference to the accompanying drawings as follows:

Figure 1 is an elevation (with the case and inclosing globe shown in section) of a mercury vapor lamp constructed according to our present invention; said lamp being shown in position ready to start *i. e.* before the current is turned on. Fig. 2 is a local view of the container or vessel for holding the mercury, etc., (which may conveniently be referred to as the "burner") shown detached from the lamp—this view showing the adjustable sleeve or means for regulat-

ing the radiating surface of the condensing chamber of said burner. Fig. 3 is local view showing another form of said container for holding the mercury.

Referring now to Figs. 1 to 3. The exhausted movable container or chamber for containing the mercury (*i. e.* the "burner") consists of a tube a horizontally disposed or thereabout of cylindrical or other suitable form in cross-section and either of the same or differing shape in cross-section throughout its length and made of glass or any suitable translucent material but for the sake of brevity we will hereinafter refer to all such materials as glass only, such glass tube a being provided at one end with an enlargement a^1 or in place of such enlargement the glass tube may be continued at this end at an angle *i. e.* sloping outwardly and upwardly so as to only allow the mercury to recede or be caused to run back into same when the tube is tilted into the position shown in Fig. 2 *i. e.* when this end a^1 is lowered or in a lower position than the other end. At the opposite end of said glass tube a to the aforesaid enlargement a^1 , etc., for receiving the mercury z when the device is started, we provide a cross tube a^2 disposed vertically or thereabout, *i. e.* practically at right angles to the aforesaid horizontal tube a the lower part of which cross-tube a^2 extends below the bottom level of the horizontal tube a (or be otherwise suitably arranged to retain some of the mercury) and has one of the electrodes located therein and in contact with the mercury in the bottom of said cross-tube a^2 while the upper end of the latter may be in connection with a condensing chamber or enlargement consisting of a glass bulb such as a^3 of a size to present a sufficient radiating surface on the one hand to enable the mercury vapor to condense sufficiently rapidly therein while on the other hand this radiation surface may be limited to prevent the mercury vapor condensing too rapidly to interfere with the proper and efficient working of the lamp; and in actual practice we have found that the radiating surface should be reduced as near as possible to zero in order to insure the most efficient working of

the lamp—or if any radiating chamber is provided, it may be formed as a cylinder (or of other suitable shape) and provided with an adjustable sleeve or envelop of low 5 heat radiating capacity by adjusting which latter more or less of said radiating surface can be covered or uncovered thus enabling adjustment of the lamp to a nicety, and the envelop may be fixed in position when the 10 desired adjustment has been obtained.

In the case illustrated the enlargement a^1 at one end of the horizontal glass tube and the condensing chamber a^5 at the other end of the glass tube as aforesaid are respectively mounted and held in metal caps a^4 and a^5 which latter are provided with lugs or inwardly turned arms a^6 forming contacts through and by means of which said glass tube is mounted in position (and the 15 mercury therein placed in circuit) in the lamp and again readily removed from the lamp for instance said lugs or arms may simply rest in the spring clips b^1 c^1 on the depending arms b c which latter are insulated from one another and to each of which one pole of the circuit is connected. These two said depending arms b c are carried on a rock-beam d pivoted at d^1 to a fixed part of the frame of the lamp in conjunction with which pivoted beam or cradle means are provided to limit the extent to which said beam can be rocked for instance beneath said pivoted beam d we may arrange adjustable stops such as screws e by 20 adjusting which latter thereby the extent of movement of the rock-beam d can be regulated. To this rock-beam d an upwardly extending arm or lever f is attached which arm at its upper end is linked at f^1 to the core or armature g of a solenoid or electro-magnet h which latter is carried on a fixed part of the frame of the lamp for example as illustrated this magnet h may be fixed to a rigid bracket i which at its upper part 25 is attached rigidly to a lug j on the inside of the top of the frame h of the lamp while the said bracket i at its lower end is bent and turned inwardly at i^1 and downwardly at i^2 to form a support for the aforesaid pivoted 30 rock-beam d and the aforesaid adjusting screws e .

l is bottom plate provided at the bottom of any suitable metal hood or casing such as h said bottom plate l being provided with 35 slots l^1 through which the aforesaid depending arms can freely pass without touching; and the parts of the lamp below said bottom plate may be inclosed in a globe m of any suitable character.

60 A spring o (or weight) may be provided if desired on or so as to operate on the core g in order to insure said core being forced out of the coil instantly the current is interrupted.

p p^1 are the terminals of the lamp by 65 which same is connected in to the main circuit.

z is the mercury.

In Fig. 2 the burner is shown with an adjustable sleeve a^8 adapted to be adjusted 70 with respect to the condensing chamber a^3 , by screwing the said sleeve a^8 on or off the screw-thread a^{10} on the support a^5 , and thus exposes or covers more or less of the said condensing chamber a^3 as desired. 75

In Fig. 3 the burner is shown with the condensing chamber reduced practically to zero or as near as possible to zero—and in this case no adjustable sleeve a^8 or other adjustable means are employed for controlling 80 the condensation of the mercury.

The operation of the lamp and burner illustrated in said Figs. 1 to 3 is as follows:—Before the current is switched on the aforesaid so-called horizontal glass tube a occupies the approximately horizontal position as shown in Fig. 1 and the body of mercury z extends along said horizontal tube and covers or makes contact with the electrodes or contacts x and y at each end 90 of said horizontal glass tube.

When current is switched on through the lamp it flows between the electrodes x and y located at opposite ends of the said horizontal glass tube a through the mercury z 95 located in said glass tube a in the position shown in Fig. 1 and at the same time the electro-magnet h is energized and the core g thereof thereby drawn up into said magnet and thus the pivoted beam d is rocked and 100 consequently the so-called horizontal glass tube a is tilted or moved into a different position so that the mercury is separated (at or near the point of junction of the horizontal glass tube a with the vertically disposed cross-tube a^2) thus leaving some of the mercury in the lower part of the cross-tube a^2 while the general body of the mercury recedes or is caused to flow back along the horizontal glass tube into the enlargement a^1 and thereby the arc is struck or 110 luminosity produced and the mercury vapor formed and the lamp continues burning, and the electro-magnet h during the burning of the lamp continues to hold the glass tube 115 a in the tilted position as long as the current continues to flow.

The mercury vapor meantime continuously condenses in the radiating chamber a^3 and the condensed mercury falls from 120 said condensing chamber toward the bottom of the cross-tube a^2 and keeps the contact therein covered and any excess of mercury rising in the cross-tube a^2 above the level of the tube a (at its junction with the 125 said cross-tube a^2) will consequently run down the said tube a toward the opposite end thereof and join the main body of mer-

cury at this latter end a^1 of the said tube a , and a continuous burning lamp is thereby made possible.

Should the current be interrupted either 5 momentarily or otherwise—immediately the current ceases the electro-magnet releases the core, the rock-beam d is consequently rocked back and the tube a and connecting parts (i. e. the burner) are consequently 10 restored to the position shown in Fig. 1 *i. e.* to their normal position which they occupied before starting the lamp whereupon the current can flow again through the mercury between the two electrodes and contacts and upon this again taking place the lamp will be automatically started up again 15 and so on.

With reference to all the drawings:—we find in practice that mercury vapor lamps 20 constructed according to our present invention may require rather more current to start them than is necessary to keep them lighted when once the mercury has been warmed up and vaporized.

25 For example a lamp having a so-called horizontal glass tube of about four inches in length and one-quarter or one-third of an inch diameter strikes up readily with about two amperes but after about 15 seconds the current may be reduced to about 0.6 amperes when the lamp will continue burning steadily with the latter current. This reduction of the current after starting may be effected in any suitable way; *e. g.* by means 30 of a switch operating a variable resistance in series with the lamp so as to control the desired variation in current with constant potential or the potential may be varied so as to vary the current in the desired manner by means of a choking coil or otherwise; 35 or the formation of the arc itself may bring about the desired reduction in current, and in practical working this is found to be the case.

40 In operating two or more of our lamps in series there would be a heavy rush of current at the instant of switching on and before the arc was struck and we may if necessary control this “starting current” 45 within the desired limits by means of a variable resistance or by varying the potential as before described.

It is obvious that we may control the 50 movement of the armature within the magnet by means of a dash-pot or in any other suitable manner or the mercury in the container may be caused to give sufficient “dash-pot” action; and this action utilized for the 55 purpose of such control.

60 We may if desired suspend two or more of our mercury vapor lamps on the rock-beam and we may connect these lamps in series with one another or in parallel the winding on the electro-magnet being varied

accordingly. In constructing these burners 65 we find that lead glass is very suitable for the purpose and that pure mercury in the container exhausted to a high degree of 70 vacuum gives excellent results, and under these conditions there is no tendency for the lead glass to melt or crack when the lamp is working with a current sufficient to 75 maintain the mercury vapor in an efficient state of incandescence; but we do not wish to bind ourselves to pure mercury or lead glass as for example impurities might with 80 advantage be introduced in the mercury or any other suitable liquid conductor may be employed instead of mercury or other qualities of glass notably Jena glass may be used 85 or quartz may be used without departing from the spirit of our present invention.

The contacts or leading-in wires or both are advantageously made of platinum and such wires or the contacts within the container should always be completely covered 85 with mercury except in certain cases one such contact may be exposed; for example, one of the contacts or electrodes might be of iron or other metal but we prefer both 90 leading-in wires to be of platinum.

From our observation of the working of these lamps; apparently, during the operation of the lamp, with a continuous current a transference of metal (mercury) takes 95 place from one electrode to the other (probably a kind of electrolytic action with metallic vapor as the electrolyte) but the loss of mercury at the one electrode and the gain 100 at the other is or may be compensated for by condensation or the overflowing of the mercury as aforesaid from the last-named electrode *i. e.* from the upper electrode to the lower one.

The enlargement a^1 (Figs. 1 to 3) in or 105 on or at or toward the end of the container may advantageously be of an internal capacity or size such that it will not quite receive all the mercury out of the container and consequently it serves to limit the extent to 110 which the mercury can be moved back or divided and thus governs the length of the arc or luminous space, and this limitation of the size of this chamber has the further result as aforesaid that it also prevents the 115 possibility of the contact in the mercury in said chamber ever becoming uncovered which is a desideratum.

We would observe that we have found that the length of the vapor arc or luminous 120 space may be determined or regulated not only by the angle or extent to which the container is tilted or moved but also by the cross-section of the enlargement a^1 and the size or extent of the radiating surface any 125 variation in which latter varies the pressure of the mercury vapor and consequently will vary the extent to which the mercury is

forced back or forced apart by said pressure, unless that extent is limited by the size of the receptacle a^1 .

The length of arc is extended or prolonged 5 up to the limits of the lamp as aforesaid; and this is controlled by means of the enlargement a^1 shown in sheets one and two; and when the internal cross-sectional area of the glass tube a is constant, and the angle 10 that the latter is tilted out of the horizontal is also constant, then the length of arc will increase as the cross-sectional area of the enlargement a^1 is increased.

When the length of the arc is controlled 15 both by the extent of inclination of the burner and also by the pressure produced within the burner then with an approximately horizontally disposed tube it is important that the latter should be in diameter about 20 three-eighths of an inch or less so as to cause that part of the mercury in the tube part of the burner to fill the bore at such part so that the mercury shall present a butt end or ends for the pressure to act upon, and with 25 this object the tube (i. e. if of larger bore than $\frac{3}{8}$ " as aforesaid) may if necessary be narrowed or restricted (i. e. "choked") as shown for example at a^1 Fig. 2.

The head of mercury produced behind the 30 arc (i. e. in the chamber a^1) by the pressure within the burner may be controlled by varying only the internal cross-sectional area of the enlargement a^1 Fig. 3 and we do not consider it is necessary for us to state here 35 what this cross-sectional area should be as it will vary according to the length of arc required, the pressure at which it is desired to maintain the vapor within or around the arc, the melting point of the translucent material around the arc path and the size of the condensing or radiating chamber if the latter is provided.

In Fig. 3 we have shown one example of a burner in full size which we have found to 45 work excellently in practice (with 0.9 amperes) connected three in series across 200 volts with about 50 ohms, steadyng resistance included in the circuit and this steadyng resistance may be a carbon filament.

We prefer to make our lamps so that the angle of inclination of the burner alone controls the length of arc and we may accordingly arrange for the mercury to run back 55 into the enlargement a^1 whenever the tube is tilted at the predetermined angle and if desired we may produce any necessary dashpot action which will tend to assist in governing the action of the armature so as to 60 retard the separation of the mercury by restricting or narrowing the bore of the tube at any suitable point for example as shown in dotted lines at Fig. 3.

When our lamps are in operation and

when the uppermost electrode is the negative electrode we make the heat radiating surface of the burner as small as possible (i. e. we do not provide any special condensing or radiating chamber) but when the uppermost electrode is made the positive 70 electrode then the loss of mercury from the electrode by transposition must be compensated for or over compensated for by providing a condensing chamber as already explained, and without this provision in course 75 of time the positive leading-in wire would become exposed and the lamp thereby damaged and we claim to be the first to have pointed out the conditions under which a mercury vapor arc which is started by tilting as described can be continuously maintained in a continuous current circuit.

If iron or other solid material is used for one electrode it is advantageous to arrange it as the negative electrode at the upper end 85 of the lamp.

The small tubes in which the arc is formed are specially suitable and advantageous for our purpose not only because they cause the mercury to fill the bore when lying in an approximately horizontal position (which is not the case with tubes of a much bigger diameter than $\frac{3}{8}$ ") but also because of the large light and heat radiating surface that they present in proportion to their cross-section, and the importance of this fact in relation to the efficiency of mercury vapor lamps has not been previously pointed out and by our invention we are thereby enabled to maintain the arc in our lamps at a very 100 much higher temperature or at a higher "light efficiency" than has heretofore been possible without melting the glass inclosing the arc; and this applies whatever translucent material is used.

This application is a division of our application Serial No. 222,148, filed August 25th, 1904.

We claim as our invention:—

1. A gas or vapor electric apparatus comprising a tube, a receptacle at one end of said tube and electrode material therein, another receptacle at the other end of said tube and electrode material therein, and a leading-in conductor for each receptacle, the bore of the tube being reduced in the neighborhood of one of the electrodes, and the receptacle at one end of the tube having an internal capacity such that it will not quite receive all the mercury out of the tube.

2. A gas or vapor electric apparatus comprising an approximately horizontal tube, a receptacle at one end of said tube and electrode material therein, a considerable portion of the receptacle being above the level of the tube, another receptacle at the other end of said tube and electrode material therein, and a leading-in conductor for each re-

ceptacle, the electrode material of one of the receptacles extending into a portion of the tube and the bore of the tube being reduced in the neighborhood of said receptacle, whereby the electrode material at that end of the tube extends into the receptacle and also into the reduced portion of the tube in the other direction, so as to form a butt end on which the pressure caused by the passage of electric current in the tube during operation may be exerted.

3. In a gas or vapor electric apparatus, the combination with a tube having a receptacle at one end and electrode material therein and another receptacle at the other end thereof and electrode material therein, a lead-

ing-in conductor for each receptacle, the bore of the tube being reduced in the neighborhood of one of the receptacles and means for causing the electrode material in the tube to fill the bore of the tube at the reduced portion, whereby the said electrode material shall produce a butt end or ends for the pressure of the vapor path to act upon.

Signed at London England, this 1st day of November 1915.
